METHOD OF PRODUCING NIPPLES

Fred W. Leuthesser, Oak Park, Ill.

Application October 9, 1935, Serial No. 44,213

2 Claims. (Cl. 29—157)

This invention which relates generally to air relief valves such as are used with steam radiators and the like, is concerned particularly with the construction of a connecting nipple which is joined to the valve casing.

A principal object of my invention is to provide for a cylindrical valve casing a nipple having a flange which may bear against the inner face of the casing wall and be secured thereto in any convenient way as by soldering. A nipple having its flange so disposed is thereby secured in a stronger and more durable manner. The construction of the nipple flange, however, presents numerous difficulties, as it must conform to the curvature of the cylindrical wall with which it co-operates. According to this invention I form at one end of the nipple a flange which is first straight, and then reshape the flange to correspond with the curvature of the casing wall to which it is connected. By so proceeding I preserve the strength of the nipple and at the same time facilitate the formation of the flange thereupon. The present invention therefore is concerned not merely with the construction of a valve casing nipple having such a curved flange, but also with the method that is employed in its manufacture.

A suggestive embodiment of this invention is set forth in the accompanying drawing, 30 wherein—

Figure 1 is a longitudinal section through an air relief valve having fitted thereto a nipple made according to this invention;

Fig. 2 is an enlarged transverse section on line 2 of Fig. 1;

Fig. 3 is a longitudinal section through the nipple as it appears when the flange is first formed thereon;

Fig. 4 is a similar view showing the flange after it has been curved to final position; and

Fig. 5 which is a view similar to Fig. 2 shows the nipple applied to a valve casing having an external offset which forms interiorly of the casing a seat for the nipple flange.

The valve structure herein shown comprises a cylindrical casing C with a dome wherein is an opening to receive a plug P. Through this plug extends an axial bore wherein is formed a valve seat 6. The plug may be secured immovably to the casing as by solder 7.

The opposite casing end may be closed as by means of a base B having a marginal flange 10 which closely surrounds the adjacent end of the casing. This base may be affixed immovably to the casing as by solder 11. Formed in the

base is an upstanding boss in the form of a truncated cone 15 having a neck 16 which is internally threaded to co-operate with the threads of a screw 17 which carries at its upper end a head 18 whose upper face is slightly convex, as shown. Upon the head is supported a float F, here shown as a sealed container, having upstanding from its upper end a pin 20 adapted to enter the bore in the plug. The upper end of the pin may engage with the valve seat 6 so as to close the opening through the bore when the float is raised off of its support upon the head 18. The lowermost position of the float is determined by adjustment of the screw 17 within the threaded neck 16.

Formed in the wall of the valve casing adjacent the base is a round opening through which is extended a cylindrical nipple N having external threads 26. At the inner end of this nipple is a flange 27 adapted to rest against the inner face of the casing wall. As the valve casing is cylindrical in form, the flange should be similarly curved in order to fit squarely thereagainst. I have accordingly so curved the flange, doing this in a way that is advantageous from various standpoints.

As best shown in Fig. 3, the nipple threads extend for the major portion of its length. The walls of this nipple, however, are of full thickness in the region 28 which is adjacent the flange 27. Extending around the nipple adjacent the base of the flange is a groove 29 which is cut into the wall at a point where it is of maximum thickness. In an early stage, the flange is straight, i. e., it lies in a single plane, as shown in Fig. 3. Thereafter the nipple is put into a shaping die which curves the flange about an axis that intersects that of the nipple (see Fig. 4). In this operation the groove is widened, and also shallowed, at two opposite points and is narrowed at two other opposite points about 90° therefrom. This is indicated clearly in Fig. 4. This variation in the width of the groove results from the displacement of metal that takes place when the flange is reshaped to curved form. By reason of the presence of this groove it is possible to produce this curvature with greater facility, the metal of the nipple thereby yielding more easily, as required at certain points, to take up its new position.

A nipple having its flange so curved is adapted to be fitted into the valve casing with the flange resting upon the inner face of its wall. When so fitted it may be secured immovably as by solder connections 30 and 31. A nipple which

is so constructed and applied to the valve casing makes a very strong connection therewith, and will not separate from the casing in response to a very strong pulling force.

5 In Fig. 5 I have shown exactly the same construction of nipple and flange except that the valve casing is exteriorly offset as at 35 to provide a seat which will accommodate the flange of the nipple. All the advantages which accrue with a 10 construction as hereinbefore described apply to this type of connection as well, and in addition the interior of the casing is preserved clear and smooth.

In the manufacture of the present nipple, I 15 prefer to start with a solid bar from which the nipple is turned. It is then annealed. The flange is next formed in a turning operation and later is shaped by a die. This shaping operation may proceed without detriment to the nipple and 20 without any impairment of its strength, due to the provision of the annular groove around the nipple which facilitates the displacement of metal

necessary for the flange to assume the curvature which has been described. Finally, as by the application of solder, the nipple is securely fixed in place and in a manner which will be leak proof.

5

I claim:

1. The method of producing a nipple having a curved flange which comprises the steps of first forming on the nipple a straight flange with an annular groove of uniform width adjacent its base and then shaping the flange into curved form with a concurrent variation of the groove width.

2. The method of producing a nipple having a curved flange which comprises the steps of first forming on the nipple a straight flange with an annular groove of uniform width adjacent its base, and then shaping the flange into curved form with a concurrent narrowing of the groove at diametrically opposite points and a concurrent widening of the groove at intermediate diametrically opposite points.
